US00D949176S

(12) **United States Design Patent** (10) **Patent No.:** **US D949,176 S**
Kennedy et al. (45) **Date of Patent:** **** Apr. 19, 2022**

(54) **ELECTRONIC DEVICE WITH GRAPHICAL USER INTERFACE**

(71) Applicant: **Apple Inc.**, Cupertino, CA (US)

(72) Inventors: **Zachery Webster Kennedy**, Marina Del Ray, CA (US); **Sean Patrick O'Brien**, San Francisco, CA (US); **Christopher I. Wilson**, San Francisco, CA (US)

(73) Assignee: **Apple Inc.**, Cupertino, CA (US)

(**) Term: **15 Years**

(21) Appl. No.: **29/795,795**

(22) Filed: **Jun. 21, 2021**

Related U.S. Application Data

(63) Continuation of application No. 29/699,538, filed on Jul. 26, 2019, now Pat. No. Des. 923,020.

(57) **CLAIM**

The ornamental design for an electronic device with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing the claimed design; FIG. 2 is another embodiment thereof; and,

FIG. 3 is a front view of an electronic device having a display screen with the graphical user interface of FIG. 1 applied to the display screen. The graphical user interface design of FIG. 2 may be similarly applied thereto.

The broken lines in the figures show a display screen or portion thereof, or an electronic device having a display screen, and form no part of the claimed design.
